ADJUSTABLE WEATHER-STRIPPED DOOR JAMB

Raymond V. Gauthier, Kissimmee, Fla.

Application November 15, 1957, Serial No. 696,748

4 Claims. (Cl. 20—11)

This invention relates to entrance enclosure structures, and more particularly to an improved door jamb structure.

The main object of the invention is to provide an improved prefabricated adjustable door jamb assembly which is simple in construction, which is easy to install, and which provides a considerable saving in time and labor in the installation thereof, as compared with the installation of conventional door framing.

A further object of the invention is to provide an improved prefabricated door jamb assembly which involves inexpensive components, which is durable in construction, which may be easily adjusted to a true plumb condition, which is neat in appearance, and which may be installed by relatively unskilled labor.

Further objects and advantages of the invention will become apparent from the following description and claims, and from the accompanying drawings, wherein:

Figure 1 is an elevational view, partly in vertical cross section, showing a door framing assembly according to the present invention with a door installed therein.

Figure 2 is an enlarged horizontal cross sectional detail view taken on the line 2—2 of Figure 1.

Figure 3 is an enlarged horizontal cross sectional detail view taken on the line 3—3 of Figure 1.

Figure 4 is a horizontal cross sectional view similar to Figure 2 but showing a modified form of installation of the door frame members.

Figure 5 is an enlarged cross sectional detail view taken on the line 5—5 of Figure 1.

Figure 6 is an enlarged front elevational view of one of the hinges employed in the assembly of Figure 1.

Figure 7 is an enlarged top view of one of the vertical door framing members employed in the assembly of Figure 1.

Figure 8 is a fragmentary, enlarged top plan view of an end portion of the top door framing member employed in the assembly of Figure 1.

Figure 9 is a side elevational view of the upper end portion of the vertical door framing member shown in Figure 7.

Figure 10 is a fragmentary side elevational view of the portion of the top door frame member shown in Figure 8.

Figure 11 is an enlarged fragmentary front elevational view, partly in vertical cross section of an upper corner joint formed by connecting the vertical frame member of Figures 7 and 9 with the horizontal door frame member of Figures 8 and 10.

Figure 12 is an enlarged horizontal cross sectional view taken on the line 12—12 of Figure 1.

Figure 13 is a vertical cross sectional view taken on the line 13—13 of Figure 12.

Figure 14 is a fragmentary side elevational view of the lower end portion of the vertical door frame member illustrated in Figures 7 and 9.

Figure 15 is a fragmentary top plan view of the end portion of a threshold member adapted to lockingly in-

2

terengage with the lower end portion of the door frame member shown in Figure 14.

Figure 16 is a cross sectional view similar to Figure 12 but showing a modified threshold arrangement wherein double threshold elements are employed.

Figure 17 is a fragmentary cross sectional view taken on the line 17—17 of Figure 16.

Figures 18 and 19 are enlarged perspective views of fragmentary portions of the opposing threshold members of Figures 16 and 17 illustrating the manner in which the opposing threshold members are interconnected.

Figure 20 is an elevational view of a hinge which may be employed in the assembly of Figure 1, in place of the hinge illustrated in Figure 6, representing a modification of the assembly with respect to the hinge and its manner of adjustable securing.

Figure 21 is an enlarged vertical cross sectional view showing a fragmentary portion of the vertical door frame member to which the hinge of Figure 20 is adjustably secured.

Referring to the drawings, and more particularly to Figure 1, 22 generally designates a door frame assembly according to this invention. The door frame assembly 25 comprises the respective vertical frame members 23 and 24 which are connected at their top ends by a horizontal frame member 25, the sill of the doorway being provided between the vertical door frame members 23 and 24 with a threshold member 26.

As shown in Figure 2, the vertical door frame member 23 is generally channel-shaped, having the outer opposing main flanges 27 and 28 and having the transverse web portions 29 and 30 which merge with an intermediate channel member 31 formed between the transverse portions 29 and 30, the channel member 31 comprising the opposing wall portions 32 and 33 and the connecting transverse wall portion 34. The outer surface of the wall portion 33 of the auxiliary channel 31 is formed with a longitudinal groove in which is secured a weather strip element 35 of suitable deformable sealing material, such as felt or the like.

The vertical frame member 23 is secured on an inner channel-shaped frame member 36 which is formed with the inwardly facing marginal channel elements 37 and 38 at its respective edges, the inturned flanges of the auxiliary channels 37 and 38 being lockingly interengagable with the inner plate member 39 of a sheet metal wall tie element, in the case of masonry wall construction, as shown in Figure 2.

Figure 4 illustrates an alternative arrangement where the assembly is employed with wood framing, in which case a pair of hook bolts 40, 40 are engaged through the vertical wall frame member 41, and are lockingly engaged with the inturned flanges 37 and 38 to secure the inner frame member 36 rigidly to the vertical frame element 41 at the doorway opening of the wall.

The inner vertical member 36 is formed with spaced inwardly extending, internally threaded anchor sleeves 42, and the outer member 23 is secured to the inner member 36 by respective fastening bolts 44 engaged through the flanges 27 and 28 of the outer member and threadedly engaged in the anchor sleeve 42 of the inner member 36.

The opposing vertical door frame member 24 is secured in place in the same manner as the door frame member 23.

The top member 25 is of the same cross sectional shape as the vertical frame members 23 and 24, the members 23 and 24 being of identical cross sectional shape, as will be apparent from Figure 1. The vertical frame members 23 and 24 are provided at their top edges with upstanding bendable prongs 45, the auxiliary channel

elements 31 of said vertical frame members being cut away, as shown at 46, whereby to define a stepped configuration at the top ends of said vertical frame members 23 and 24. The top frame member 25 is similarly cut away at its end, as shown at 47, whereby the end of its auxiliary channel element is inwardly offset sufficiently to allow the end of the horizontal top member 25 to fit over the top end of the adjacent vertical frame member 23 or 24. The horizontal surfaces of the top member 25 engageable with the top end edges of the members 23 and 24 are formed with apertures 48 in which the upstanding lugs 45 are received, said upstanding lugs being thereafter bent over to securely clamp the horizontal top member 25 to the top ends of the vertical frame members 23 and 24, as shown in Figure 11.

The outer surface of the wall of the auxiliary channel of the top member 25 is provided with a sealing strip 49 of weather strip material, similar to the weather strip elements 35 provided in the channel wall portions 33 associated with the vertical frame members 23 and 24, the strip 49 being coplanar with the weather strip elements 35, as shown in Figure 1, whereby to sealingly engage with a door 50 hinged in the doorway structure.

The threshold member 26 is provided with the depending marginal rib elements 51 and 52 which are formed with dovetailed grooves, similar to the dovetailed grooves provided for the weather strip elements 35 and 49, as illustrated in Figure 18, in which are received respective deformable sealing strips 53 and 54 engageable with the floor surface beneath the threshold member 26. The ends of the threshold member 26 are formed with spaced lugs 55, as shown in Figure 15, which are lockingly receivable in apertures 56 provided in the lower end portions of the web elements 34 of the side frame members 23 and 24, as shown in Figure 14. The threshold member 26 is formed in its vertical end surface 58 with a dovetailed groove in which is secured a deformable weather strip element 59 which is thus supported in coplanar relationship with the weather strip elements 35 and 49 and is sealingly engageable with the door 50.

An auxiliary threshold member 60 may be employed, as shown in Figures 16, 17, 18 and 19, the auxiliary threshold member 60 being fastened to the underlying floor surface by suitable screws 61, the threshold member 60 being generally similar in shape to the main threshold member 26 and opposing same, the auxiliary threshold member 60 being provided with the spaced longitudinal bottom ribs 62 and 63 at its respective margins, said ribs being formed with dovetailed grooves in which are secured deformable sealing strips 64 and 65, as shown in Figure 19. The end surface of the threshold member 60 opposing the main threshold member 26 is formed with a longitudinal groove 65 shaped and located to receive the weather strip element 59 of the main threshold member 26, so that the mating threshold elements 60 and 26 will be substantially sealingly united in the manner illustrated in Figure 17. The top surface of the auxiliary threshold member 60 is formed with a dovetail groove in which is secured an outwardly facing weather strip element 66 adapted to sealingly engage the bottom edge of the door 50 employed in the doorway.

The door 50 is supported on spaced hinges 70, said hinges being secured to the vertical door frame member 23. Thus, the hinges 70 comprise respective leaves 71 and 72. The leaves 71 are engaged through vertical slots formed in the flange 24 of the frame member 23 and are secured to the inside surface of the web element 30 by screws 74 engaged through the web element 30 and threadedly engaged with the leaf 71 in tapped openings 75 provided therein. The leaf 72 of each hinge 70 is provided with the horizontally elongated slots 76 which are employed to fasten leaf 72 to the edge of door 50,

as by wood screws 77 engaged through the slots 76 and embedded in the edge portion of door 50, as shown in Figure 4. The slots 76 are beveled, as shown in Figure 6, whereby to receive the screw heads and to provide a flush configuration of the screw heads with respect to the leaf 72. The provision of the horizontally elongated slots 76 allows the door 50 to be adjusted relative to the hinge pin before the screws 77 are tightened.

Each leaf member 71 is provided at its intermediate portion with an arcuate projection 78 which extends through an aperture provided therefor in the web element 30, as shown in Figure 5, and which is receivable in a correspondingly-located aperture 79 provided in the mating hinge leaf 72, the door 50 being recessed at its edge to receive the projection 78 when the door is in its closed position, as shown in Figure 5.

Alternatively, the web element 30 may be provided with the horizontally elongated slots 76', as shown in Figure 21, and the leaf 72 of each hinge may be provided with the threaded openings 75', whereby the leaves 72 are engaged through the vertical slots in the flange 28 and are adjustably secured to the member 23 by bolts engaged through the slots 76' and threadedly engaged in the tapped opening 75'. The leaf 71 may be thus provided merely with openings through which screws 77 may be passed to secure the leaf 71 to the edge of a door 50. Figures 20 and 21 illustrate the above described alternative hinge construction, whereby adjustment of the door relative to the member 23 may be obtained.

As shown in Figures 1 and 3, a conventional door lock assembly 80 may be employed in the free vertical marginal portion of the door 50, the door lock having the usual bevel latch bolt 81 which is engageable with an apertured striker plate 82 secured to the outer auxiliary web element 30' of the vertical frame member 24. The web element 30' is apertured to receive the bolt 81, as shown in Figure 3. Said web element 30' is preferably recessed to receive the striker plate 82, in the manner illustrated in Figure 3.

As shown in the drawings, the auxiliary channels 31 are preferably located midway between the opposite side flanges 27 and 28 of the side frame members 23 and 24 and the horizontal top frame member 25, so that a door may be mounted on either side of the door frame, the marginal portions of the sides and top of the door being receivable in recesses defined on opposite sides of the auxiliary channels. Thus, slots may be provided in either the main side flanges 28 or the main side flanges 27 to receive the leaves of the hinge units for securing the hinge units to the side frame members.

The flanges of the inner channel elements 36 are sufficiently flexible so that they may be flexed outwardly sufficiently to engage around the side edges of the plate elements 39 in the form of installation shown in Figure 2 or around the hook elements 40 in the form shown in Figure 4.

The inner channel members 36 are preferably filled in any suitable manner, for example, with mortar, so that they become completely rigid after installation and provide a secure support for the frame members which are subsequently fastened thereto.

As will be readily apparent, the door jamb assembly can be adjusted to an absolutely plumb condition by the adjustment of the fastening bolts 44. Furthermore, the adjustability of the hinges allows the associated door to be adjusted so that it will seat properly all around its periphery, providing a proper seal against the adjacent deformable weather strip elements.

The provision of the arcuate studs 78 and their cooperating apertures 79 makes it impossible to remove a closed door without first unlocking the door at the lock side thereof and pulling it ajar. For various reasons doors are sometimes hung to open outwardly. In areas where extremes of wet and dry climatic conditions are

encountered, the door itself must be hung with a relatively large amount of clearance to allow for swelling and shrinkage of the door. With a conventional hinge it may be possible to remove a locked door by removing the hinge pins and opening the door from its hinged side. This cannot be done with the hinge structure of the present invention.

While certain specific embodiments of an improved door frame structure have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A door frame comprising inner channel-shaped vertical side members adapted to be secured to the vertical margins of a doorway opening, a pair of channel-shaped vertical side members engaged over said first-named side members, a plurality of horizontal, inwardly extending internally threaded sleeves on each side flange of said first-named vertical side members, respective bolts engaged through the side flanges of the second-named vertical side members and threadedly engaging in said sleeves, adjustably securing the side flanges of said second-named vertical side members to the side flanges of said first-named vertical side members, a channel-shaped top member connecting the top ends of said side members, and a threshold member connecting the lower ends of said side members, said side members and top member being of identical cross sectional shape and having their web portions located inwardly to define a door opening, auxiliary channels formed on said web portions and being substantially narrower than said web portions, whereby to define a peripheral recess adjacent thereto around the frame to receive the marginal portions of the sides and top of a door, and a plurality of hinges adjustably secured to a portion of one of said side members for hingedly connecting a door to said frame.

2. A door frame comprising inner channel-shaped vertical side members adapted to be secured to the vertical margins of a doorway opening, a pair of channel-shaped vertical side members engaged over said first-named side members, a plurality of horizontal, inwardly extending internally threaded sleeves on each side flange of said first-named vertical side members, respective bolts engaged through the side flanges of the second-named vertical side members and threadedly engaging in said sleeves, adjustably securing the side flanges of said second-named vertical side members to the side flanges of said first-named vertical side members, a channel-shaped top member connecting the top ends of said side members, and a threshold member connecting the lower ends of said side members, said side members and top member being of identical cross sectional shape and having their web portions located inwardly to define a door opening, auxiliary channels formed on said web portion substantially midway between the side flanges of said second-named side members and being substantially narrower than said web portions whereby to define peripheral recesses adjacent thereto around the frame to receive the marginal portions of the sides and top of a door, and a plurality of hinges adjustably secured to a portion of the web of one of said second-named side members for hingedly connecting a door to said frame.

3. A door frame comprising inner channel-shaped vertical side members adapted to be secured to the vertical margins of a doorway opening, a pair of channel-shaped

vertical side members engaged over said first-named side members, a plurality of horizontal, inwardly extending internally threaded sleeves on each side flange of said first-named vertical side members, respective bolts engaged through the side flanges of the second-named vertical side members and threadedly engaging in said sleeves, adjustably securing the side flanges of said second-named vertical side members to the side flanges of said first-named vertical side members, a channel-shaped top member connecting the top ends of said side members, and a threshold member connecting the lower ends of said side members, said side members and top member being of identical cross sectional shape and having their web portions located inwardly to define a door opening, auxiliary channels formed on said web portions substantially midway between the side flanges of said second-named side members and being substantially narrower than said web portions, whereby to define peripheral recesses adjacent thereto around the frame to receive the marginal portions of the sides and top of a door, deformable weather strip elements secured to said auxiliary channels facing and extending around at least one of said peripheral recesses, a plurality of hinges adjustably secured to a portion of the web of one of said second-named side members for hingedly connecting a door to said frame, and a deformable weather strip element secured to said threshold member in substantially coplanar relation to the first-named weather strip elements.

4. A door frame comprising inner channel-shaped vertical side members adapted to be secured to the vertical margins of a doorway opening, a pair of channel-shaped vertical side members engaged over said first-named side members, a plurality of horizontal, inwardly extending internally threaded sleeves on each side flange of said first-named vertical side members, respective bolts engaged through the side flanges of the second-named vertical side members and threadedly engaging in said sleeves, adjustably securing the side flanges of said second-named vertical side members to the side flanges of said first-named vertical side members, a channel-shaped top member connecting the top ends of said side members, and a threshold member connecting the lower ends of said side members, said side members and top member being of identical cross sectional shape and having their web portions located inwardly to define a door opening, auxiliary channels formed on said web portions substantially midway between the side flanges of said second-named side members and being substantially narrower than said web portions, whereby to define peripheral recesses adjacent thereto around the frame to receive the marginal portions of the sides and top of a door, respective deformable weather strip elements secured to said auxiliary channels facing and extending around one of said peripheral recesses, a plurality of hinges adjustably secured to a portion of the web of one of said second-named side members for hingedly connecting a door to said frame, and an additional deformable weather strip element secured in the top surface of said threshold member and being engageable with the bottom edge of a door fastened to said hinges and receivable in said door frame.
